SHOE BOTTOM IRONING UNIT

Sidney J. Finn, Beverly, Mass., assignor to United
Shoe Machinery Corporation, Paterson, N. J.,
a corporation of New Jersey

Application January 17, 1938, Serial No. 185,347

30 Claims. (Cl. 12—51)

This invention relates to machines for pressing the bottoms of shoes and in some aspects has more particularly in view the provision of improved means for applying pressure and heat to the marginal portion of upper materials (hereinafter referred to inclusively as the upper) upon an insole before the outsole is applied to the shoe.

In the manufacture of shoes in which the upper is laid inwardly over the insole in substantially parallel relation to the bottom of the shoe it is often the practice to subject the overlaid margin of the upper to heat and to pressure directed both heightwise of the shoe and inwardly from the edge of the shoe bottom to flatten the margin of the upper evenly and to iron it smooth on the insole without any wrinkles or other surface irregularities before placing the outsole on the shoe. In thus treating the marginal portion of the upper it is desirable that substantially uniform pressure be applied to the margin along the opposite sides of the forepart, shank and heel-end portions of the shoe so that the outsole when applied to the shoe will lie uniformly close to the upper and insole along these different portions of the shoe bottom. Various features of the present invention are to be recognized in a novel organization of means for accomplishing that result. For the purpose in view the machine herein shown is provided with heated devices that are arranged to engage the bottom of the shoe along the opposite sides of the forepart, shank and heel-end portions, respectively, and are relatively adjustable heightwise of the shoe to accommodate shoes of different styles, that is, shoes the curvature of the bottom faces of which vary considerably heightwise of the shoe by reason of the fact that the shoes are mounted on lasts designed to accommodate heels of different heights. In the construction shown, the devices or units are arranged in pairs to operate respectively on the bottom of the forepart, shank and heel-end portions of the shoe, the different pairs of units being connected together for relative rotation about different axes extending laterally of the shoe and the units of each pair being also movable simultaneously inward toward each other in wiping engagement with the overlaid margin of the upper in response to resistance to movement of the shoe to the pressure applied. As herein illustrated, each unit comprises a holder and a shoe-engaging plate of resilient metal shaped to conform substantially to the heightwise curvature of the portion of the shoe bottom engaged thereby, the different pairs of resilient plates being arranged to support a shoe placed thereon bottom

downward and the forepart and heel-engaging plates having portions curved similarly to and overlapping the shank-engaging plates to provide continuous engagement with the overlaid margin of the upper along the opposite sides of the 5 bottom of the shoe from its toe to its heel-end portion. By relative adjustment of the forepart, shank and heel-end units heightwise of the shoe the contour lengthwise of the shoe defined by the shoe-engaging plates may be varied in accordance with variations in the heightwise curvature of the bottoms of shoes of different styles, the different pairs of resilient plates being arranged to bend and conform themselves more closely to the contour of the shoe as the pressure is applied against the resistance of separate spring means of equal capacity the yielding of which is limited to permit relatively heavy pressure to be applied to the shoe.

The above and other features of the invention, 20 including various novel details of constructions and combinations of parts, will now be more particularly described by reference to the accompanying drawings and pointed out in the claims.

In the drawings,

Fig. 1 is a view in front elevation of the upper left-hand portion of a machine in which the invention is embodied, with parts broken away;

Fig. 2 is a view in left-hand side elevation of the portion of the machine shown in Fig. 1;

Fig. 3 is a plan view of the shoe bottom pressing or ironing means and parts associated therewith;

Fig. 4 is a view partly in left-hand side elevation and partly in section showing the ironing units for engaging the bottom of the forepart, 35 shank and heel-end portions of the shoe at one side only with the shoe under pressure in the machine;

Fig. 5 is a perspective view of the ironing units shown in Fig. 4 with the ironing members removed; and

Figs. 6 and 7 are cross-sectional views through the forepart and shank ironing units respectively, illustrating the positions of the parts at the end of the ironing operation.

The invention is illustrated as applied to a machine of the type disclosed in application for Letters Patent of the United States Serial No. 201,790, filed April 13, 1938, in the name of A. A. Lawson, although it is to be understood that the 50 invention is not limited to organizations of that particular character. The machine is provided with a base 20 to which there is secured by screws 22 (Fig. 2) a bracket 24 for supporting a pair of vertical rods 26 which support adjustably near 55

their upper ends a crosshead (not herein shown) on which there is adjustably mounted for movements in directions lengthwise of the shoe a carrier having depending arms 28, one of which is shown in Fig. 4, carrying a laterally extending rod 30 on which there is mounted a shoe support or jack which is substantially like that fully shown and described in Letters Patent No. 2,095,245, granted on October 12, 1937, on an application of mine, this jack serving to support the shoe against pressure applied on its bottom face. The jack comprises a shoe rest 32 (Fig. 4) for engaging the shoe at the top of the forepart and a heel-end support 34 which engages the top of the cone of the last. In order to hold the shoe effectively against tipping movement laterally of the shoe as pressure is applied to its bottom face the heel support 34 includes the last pin 36 arranged to extend into the spindle hole in the heel end of the last. The shoe rest 32 comprises a leather covered pad 38 of rubber or other suitable material which is hollowed out laterally of the shoe and is mounted on a block 40 adjustably secured to a second block 42 mounted for sliding movements in directions lengthwise of the shoe on a rocking member 44. The member 44 is mounted on the rod 30 supported by the depending spaced arms 28 of the above-mentioned carrier, the rod 30 extending through an elongated slot 43 in the member 44. Pivotedly mounted on the block 42 is a spring controlled latch 46 arranged to engage any one of a series of recesses 48 formed in the member 44 to hold the block 42 in adjusted position lengthwise of the shoe. Formed on the block 42 is a dovetail-shaped tongue 50 extending laterally of the shoe and arranged to enter a similarly shaped groove in the block 40. The block 40 is held in adjusted position laterally of the shoe on the block 42 by means of set screws 52 carried by the block 40 and arranged to engage the tongue 50, lock nuts 54 being provided for holding the set screws in locking engagement with the tongue. It will be readily seen that the above construction permits the shoe rest 32 to be adjusted in directions both lengthwise and widthwise of the shoe as required for shoes of different sizes and styles.

The heel-end support 34 for engaging the top of the cone of the last is freely movable in directions widthwise of the shoe along guideways formed in a holder 56, a screw 58 in the holder being provided for limiting such movement of the heel-end support relatively to the holder. For permitting free swinging movements of the holder 56 in directions lengthwise and heightwise of the shoe, there are pivotally connected to the opposite sides of the holder equal links 60 the ends of which remote from the holder are pivotally connected to a pair of equal links 62 pivotally mounted one on each side of the member 44 on a pin 64 carried by this rocking member (Fig. 4). Normally the links 60, 62, are held in a substantially straightened condition by springs 66 only one of which is shown in Fig. 4 with the links 62 in engagement with the opposite end portions of a pin 68 carried by the member 44 and with the holder 56 in engagement with the loop-shaped end of a rod 70 projecting from one end of the member 44. As more fully disclosed in the above-mentioned Letters Patent No. 2,095,245, the rocking member 44 is held normally in a substantially horizontal position with the heel pin 36 substantially vertical by means of a chain 72 connected by a spring (not herein shown) to the above-mentioned crosshead.

Mounted on the rods 26 is a slide 74 (Fig. 1) having formed thereon a collar 76 connected by screws 78 to a piston 80 slidably mounted in a cylinder 82 formed integral with the bracket 24. The piston is moved upwardly in the cylinder to impart upward movement to the slide 74 by power through fluid pressure means not herein shown since it is fully disclosed in the above-mentioned application Serial No. 201,790. Slidably mounted on the rods 26 above the slide 74 is a casting 84 supported by a spring 86 which is arranged to yield in response to resistance of the shoe to the pressure applied. At its lower end the spring 86 engages a shoulder 88 formed within a central recess 90 in the slide 74 and at its upper end the spring 86 engages a shoulder 92 within a recess 94 in the casting 84 in vertical alinement with the central recess 90. Initially the spring 86 is under slight tension and acts to hold the casting 84 in spaced relation to the slide 74 determined by the effective length of a bolt 96 which is carried by the casting 84 and extends downwardly through an opening in the slide 74, the head 98 of the bolt engaging a shoulder 100 on the casting 84 and a nut 102 threaded on the opposite end of the bolt 96 engaging a finished surface 104 on the slide 74. The casting 84 serves to support shoe bottom pressing or ironing devices arranged to engage the bottom of the shoe along the opposite sides of its forepart, shank and heel-end portions. As more particularly hereinafter described, the pressing devices are relatively adjustable heightwise of the shoe to accommodate shoes of different styles and as herein illustrated the devices or units are arranged in pairs to act respectively on the bottom of the forepart, shank and heel-end portions of the shoe. The ironing units for engaging the lasted margin of the upper at the opposite sides of the forepart, each comprising a holder 106 (Figs. 2, 3 and 4), are pivotally and slidably mounted upon a shaft 108 supported by upwardly extending arms 110 and bosses 112 on the casting 84, the shaft extending through a boss 114 formed on each of the holders 106 (Fig. 1). Formed also on each of the holders 106 is a boss 116 which is slotted to receive a bushing 118 on the shaft 108 and is counterbored to receive the head 120 of the bushing. Secured to each holder 106 by screws 122 (Fig. 6) is a thin shoe-engaging plate 124 of resilient metal and a relatively thick resilient metal plate 126 for supporting the plate 124, these plates being mounted in superposed contiguous relation and being shaped substantially to conform to the lengthwise curvature of the bottom of the forepart of a shoe. Extending outwardly from the inner edge of the plate 126 in directions substantially normal to the edge curvature of the forepart of a shoe are a plurality of slots 128 which divide the plate into a series of fingers 130 (Fig. 3). The outer edges of the plates 124, 126 engage a shoulder 132 on the holder 106 and secured to the holder by screws 134 is a member 136 having curved ribs 138, 140 formed thereon for limiting the downward movement of the fingers 130, the rib 140 being arranged to engage the inner end portions of the spring fingers 130 with the rib 138 in engagement with the downwardly bent fingers 130 at the toe end in locations beyond the outer edge of the last bottom.

Each heel-end ironing unit comprises a holder 142 (Fig. 4) slidably mounted upon a support 144 pivotally connected at 146 to a plate 148 secured by screws 150 to the casting 84. Secured to the holder 142 by screws 152 is a thin shoe-engag-

ing plate 154 of resilient metal and a relatively thick resilient metal plate 156 which acts as a support for the plate 154, the plates 154 and 156 being substantially flat for engagement with the lasted margin of the upper along the sides of the heel-end portion of the shoe bottom. Extending outwardly from one edge of the plate 156 in directions substantially normal to the edge curvature of the heel end of the shoe are a plurality of slots 158 which divide the plate into a series of fingers 160 downward movement of which is limited by a forwardly extending plate 162 underlying the inner end portions of the fingers 160 and secured to the holder 142 by screws 164. At their outer edges the plates 154, 156 engage a shoulder 166 on the holder 142. Overlying the plate 152 and arranged to engage the lasted margin of the upper at the extreme rear end portion of the shoe is a thin flexible resilient plate 168 secured by screws 170 to an upwardly extending member 172. The member 172 is fastened to the end face of the pivoted support 144 by screws 174 (Fig. 1) which serve also to secure to the end face of the support an inverted substantially L-shaped member 176 (Fig. 4) the forwardly extending portion 178 of which is arranged to engage the holders 142 of the heel-end ironing units in laterally extending slots 180 formed in the holders. The shank ironing units each comprises a holder 182 (Fig. 5) having formed thereon bosses 184, 186 bored to receive pivot pins 185, 187 (Fig. 2) carried by bosses 188, 190 formed respectively on the holders 106, 142 of the forepart and heel-end ironing units, the bosses 188, 190 being counterbored to receive the heads of the pivot pins and set screws 192, 194 being provided for holding the pins 185, 187 against endwise movement in the bosses. Formed on each holder 182 are curved surfaces 196, 198 (Figs. 4 and 5) arranged to engage similarly curved seats 200, 202 formed respectively on the holders 106 and 142, the curved surface 196 and its seat 200 being concentric with the axis of the pin 185 and curved surface 198 and its seat 202 being concentric with the axis of the pin 187. The holder 182 has also formed thereon a plurality of flat surfaces 204 (Fig. 4) on which rest a plurality of U-shaped springs 206 the inner end portions of which are held in spaced relation by pins 208 (Fig. 7) extending upwardly from the holder 182 and through the lower arms of the U-shaped springs 206. Surrounding each of the pins 208 between the lower and upper arms of each of the U-shaped springs is a compression spring 210. At their outer closed ends the U-shaped springs are held in spaced relation by fingers 212 formed on a member 214 secured to the holder 182 by screws 216. Overlying the U-shaped springs 206 is a thin shoe-engaging plate 218 of resilient metal shaped to conform substantially to the lengthwise curvature of the shank portion of the shoe. The plate 218 is fastened by rivets 220 to the inwardly extending arms 222 of a spring clip 224 having an upwardly bent central portion 226 through which extends a shouldered screw 228 threaded into the holder 182 (Fig. 7). Near its inner end each U-shaped spring 206 has projecting upwardly from its lower arm a shouldered pin 230 riveted to the lower arm and arranged by engagement with the upper arm of the U-shaped spring to limit downward bending of the inner portion of the shoe-engaging plate 218.

In the illustrated construction, the shoe-engaging plate 124 of each forepart unit extends

somewhat heelwardly of the junction of the forepart and shank portions of the shoe, the heelwardly extending portion 232 (Fig. 3) of the plate 124 being curved similarly to and overlying the shank ironing plate 218. Overlying the shank ironing plate 218 at its rear end is the toewardly projecting portion 234 of the heel-end ironing plate 154, this projecting portion being also curved similarly to the shank ironing plate. As herein shown, the forepart, shank and heel-end ironing units for engaging the lasted margin of the upper at the opposite sides of the shoe bottom are mounted on the casting 84 between side plates 236 each of which is provided at its forward end with a depending portion 238 (Fig. 2) which is slotted to receive the bushing 118 and is counterbored to receive a head 240 formed on the outer end of the bushing. Extending through an elongated slot 242 in each side plate 236 is a shouldered screw 244 threaded into the holder 142 of the heel-end ironing unit, a washer 246 being provided between the head of the screw and the side plate. By reason of their overlapping relation the ironing plates 124, 218 and 154 of the forepart, shank and heel-end units are arranged to engage the lasted margin of the upper along the opposite sides of the shoe bottom continuously from its toe to its heel-end portion, the flexible plate 168 engaging the lasted margin of the upper at the extreme rear end portion of the shoe. The ironing plates 124, 218 and 154 are long enough to accommodate shoes of different sizes and preferably the ironing plates 124 of the forepart units are shaped to conform nearly to the lateral curvature of the bottom of the forepart of the shoe.

In order to accommodate shoes of different styles, that is, shoe mounted upon lasts designed to accommodate heels of different heights, means is provided, which will now be described, for relatively adjusting the forepart, shank and heel-end units heightwise of the shoe to vary the lengthwise contour of the ironing plates 124, 218 and 154 in accordance with variations in the lengthwise curvature of the bottom faces of shoes of different styles. As shown, particularly in Fig. 2, the holder 106 of one of the forepart ironing units is provided with a circular seat for the ball-shaped upper end of a rod 248 which is threaded into a sleeve 250 recessed to receive a projection 252 formed on a rod 254 (Fig. 2) which extends downwardly through an enlarged opening 256 in a laterally extending shaft 258 supported by depending ears 260 on the casting 84. The ball-shaped end of the rod 248 is held in engagement with its seat by means of a plate 262 secured to the holder 106 by screws 264 (Fig. 4). The rod 254 is pinned to the sleeve 250 (Fig. 2) and has a curved shouldered portion 266 engaging a similarly shaped seat formed on the shaft 258. Pinned to the rod 254 is a collar 268 engaging a flat surface 270 on the shaft 258. Surrounding the rod 254 between a flange 272 formed on a hand wheel 274 pinned to the lower end of the rod and the flat surface 270 is a compression spring 276 which acts to hold the rod 254 frictionally against free turning movement. Formed on the holder 106 to which the rod 248 is connected are laterally extending projections 278 (Fig. 5) arranged to engage finished surfaces on the bottom face of the holder 106 of the forepart ironing unit that engages the lasted margin of the upper at the opposite side of the shoe bottom. It will be

evident that by rotation of the hand wheel 274 the forepart holders 106 may be swung about the axis of the shaft 108 to lower or raise the pivot pins 185. As the pivot pins 185 are thus raised or lowered the forepart and shank holders 106, 182 are rotated relatively to one another about the axis of the pins 185 to vary the angle between the ironing plates 124 of the forepart units and the ironing plates 218 of the shank units and thus to vary the contour defined by the plates 124, 218 and 154 lengthwise of the shoe in accordance with variations in the heightwise curvature of the bottoms of shoes mounted upon lasts designed to accommodate heels of different heights. For the convenience of the operator there is pivotally connected to the casting 84 a pointer 280 (Fig. 2) which is arranged to cooperate with a scale 282 on an arc-shaped member 284 fastened to the casting 84 and to indicate the different adjusted positions of the forepart ironing units in operating upon shoes mounted upon lasts designed to carry heels of different heights, the pointer being swung as the forepart units are adjusted by means of an arm 286 connected to one of the holders 106 by a screw 288 extending through an elongated slot 290 in the arm. It will be understood that as the forepart units are thus adjusted the shank and heel-end units may move lengthwise of the shoe by reason of the slotted connection between the holders 142 of the heel-end units and the member 176. In order that the shank and heel-end ironing units may be adjusted relatively to the forepart units as may be necessary in operating upon shoes designed to carry comparatively high heels, there is connected to the support 144, on which rest the heel-end ironing units, a rod 292 (Figs. 1 and 2) which extends downwardly through a central bore in a shaft 294 supported by depending ears 296 on the casting 84. The rod 292 is threaded into a yoke 298 which extends through an enlarged opening in the plate 148 and is pivotally connected at 295 to the support 144. The rod 292 is held against endwise movement relatively to the shaft 294 by means of a collar 300 formed on the rod and engaging a flat surface 302 on the shaft and a collar 304 pinned to the rod and engaging a flat surface 306 formed on the opposite side of the shaft. Pinned to the lower end portion of the rod 292 is a hand wheel 308 for turning it and surrounding the rod between a flange 310 on the hand wheel and the flat surface 306 on the shaft 294 is a compression spring 312 which tends frictionally to hold the hand wheel against turning movement. It will be understood that by turning the hand wheel 308 the support 144 may be swung about its pivot to vary the angle between the heel-end ironing plates 154 and the shank-ironing plates 218. As the support 144 is thus swung the pivot pins 187 are raised or lowered to move the shank ironing units relatively to the forepart ironing units to give the ironing plates 124, 218 and 154 the required pronounced longitudinal contour. A pointer 315 secured to the plate 148 by screws 317 (Figs. 2 and 4) and cooperating with a scale 319 on the member 176 indicates different adjusted positions of the heel-end ironing units.

Each side plate 236 is formed integral with a pair of slides 314 (Figs. 1 and 3) mounted in guideways 316 formed in the casting 84, each slide being held in its guideway by a cover plate 318 fastened to the casting 84 by screws 320.

Arranged to engage each slide 314 in a recess

322 formed in the slide is the rounded upper end of one arm 324 of a bell-crank lever 326, the other arm of which is connected by a link 328 to the slide 74. When the machine is initially at rest the forepart, shank, and heel-end ironing units are held in their outermost positions by the side plates 236 and the above-described connections to the slide 74. As thus positioned, the ironing plates 124, 218 and 154 are arranged to receive and support a previously lasted shoe presented initially by the operator bottom downward by engagement with the overlaid marginal portion of the upper along the opposite sides of the shoe from the toe end to the heel end of the shoe, with the extreme rear end portion of the shoe in engagement with the plate 168. It will be understood that the last and shoe will have been previously mounted on the heel pin 36 and that the holder 56 will have been moved with the last and shoe as the shoe is placed initially on the ironing plates 124, 218 and 154. It will be understood also that in the upward movement of the slide 74 the shoe and the holder 56 are first moved into engagement respectively with the shoe rest 32 and with an abutment 330 formed on the member 44 before any substantial amount of pressure is applied to the bottom of the shoe and that the member 44 may rock more or less about the axis of the pin 30 to move the shoe rest 32 into engagement with the shoe or the abutment 330 into engagement with the holder 56 as may be necessary to accommodate lasts of different heights. With the shoe rest 32 in engagement with the shoe and the abutment 330 in engagement with the holder 56, the pivoted member 44 is moved upwardly with the last and shoe until its curved upper edge (not herein shown) engages a correspondingly curved seat on the previously-mentioned carrier. Thereafter the member 44 is held against further upward movement and is also held frictionally against further rocking movement and in response to the pressure of the shoe upon them the plates 124, 218, 154 and 168 are flexed to conform more closely to the contour of the shoe bottom and yield downwardly against the resistance of the spring fingers 130, the U-shaped springs 206 and the spring fingers 160. Downward yield of the spring fingers 130, the U-shaped springs 206 and the spring fingers 160, respectively, is limited by the curved ribs 138, 140, the pins 230 and the plates 162, to permit relatively heavy pressure to be applied to the shoe through the spring fingers 130, 160 and the U-shaped springs 206. Preferably the spring fingers 130, the U-shaped springs 206 and the spring fingers 160 are of substantially the same capacity so that substantially uniform pressure is applied along the opposite sides of the shoe bottom. In the continued upward movement of the slide 74 the pressure of the plates 124, 218 and 154 on the overlaid margin of the upper is progressively increased as the spring 86 is compressed until abutments 338 on the slide 74 engage abutments 340 on the casting 84. Thereafter relatively heavy pressure is applied to the shoe in the continued upward movement of the slide 74 as fluid is supplied to the cylinder 82 to raise the piston 80. As the spring 86 begins to yield in the upward movement of the slide 74 in response to the pressure of the shoe on the ironing plates, the links 328 act to swing the bell-crank levers 326 in directions to move the side plates 236 and the forepart, shank, and heel-end ironing units at the opposite sides of the shoe toward each other, the ironing plates 124, 218 and 154 being moved into engagement with the shoe rest 32 and the abutment 330 on the casting 84.

218 and 154 being thus moved bodily inward to iron the overlaid margin of the upper along the sides of the forepart, shank, and heel-end portions of the shoe.

5 In order that the ironing plates 124 of the forepart units will act on the overlaid margin of the upper around the toe end of the shoe the inner edges of the plates when the forepart units are at their outermost positions are substantially parallel to the longitudinal median line of the forepart of the shoe and are cut away rearwardly of the toe portion of the shoe to permit the toe-end portions of the plates 124 to move into engagement with each other as they complete their inward movements. Secured to the holder 106 of one of the forepart units by means of the screws 122 is a thin flexible resilient plate 342 (Fig. 3) which extends inwardly between the toe portion of the ironing plate 124 and its supporting plate 126 at one side of the shoe, the inner end portion of the plate 342 extending also between the toe portion of the ironing plate 124 and its supporting plate 126 at the opposite side of the shoe when the forepart units are in their outermost positions. The plate 342 bridges the gap between the inner edges of the toe end portions of the ironing plates 124, thus affording substantial insurance that the overlaid margin of the upper at the extreme toe end will not be pinched between the ironing plates 124 as the toe end portions of these plates are brought together at the completion of their inward movements. Marking of the upper by the inwardly moving plates 154 at the extreme heel-end portion of the shoe is prevented by the plate 168 which as shown in Fig. 3 is supported at each side of the shoe at its forward end by a spring clip 344 fastened to the holder 142 by one of the screws 152. In order to eliminate any possibility of marking the upper at the opposite sides of the shoe by the inwardly moving plates 124 and 154, the forward edge faces of the projections 232 on the plates 124 and the rear edge faces of the projections 234 on the plates 154 as well as the forward edge faces of the plate 168 are inclined at an angle to the direction of inward movement of the ironing plates.

65 In order to assist in ironing the overlaid margin of the upper free from wrinkles and setting it in lasted position, the machine herein shown is provided with means for maintaining the ironing plates in a heated condition. For this purpose there is secured to each of the holders 106, 182 and 142 at one side of the shoe, an electrical heating device 346 (Figs. 4 and 5) that extends inwardly beneath the ironing plates of the unit and also beneath the ironing plates of the corresponding unit at the opposite side of the shoe, the devices 346 being connected by suitable electrical connections to any convenient source of electrical energy for heating them. The ironing members of each unit are heated partly by radiation and partly by heat conducted to them from the holders 106, 182 and 142.

70 It will be understood that in the use of the machine for pressing or ironing the bottoms of shoes of different styles the contour of the ironing plates 124, 218 and 154 lengthwise of the shoe may be varied in accordance with variations in the heightwise curvature of the bottoms of shoes of different styles by movement of the hand wheels 274 and 308 to raise or lower the pivot pins 185 and 187 and thus to rotate the holders 106, 182 and 142 relatively to one another about the axes of the pins 185 and 187 which, as previously

pointed out, are located substantially at the junction of the forepart and shank portions and at the junction of the shank and heel-end portions of the shoe. In the operation of the machine the operator, after adjusting the ironing plates 124, 218 and 154 for the style of shoe to be operated upon, mounts a last and shoe on the heel pin 36, swings the holder 56 toward the shoe rest 32 and also moves it heightwise of the shoe to carry the shoe bottom downward into engagement with the ironing plates which serve to locate the shoe properly lengthwise in the machine, the operator positioning the shoe on the ironing plates in proper relation widthwise of the machine. In the upward movement of the slide 74 after the last 15 and shoe and the holder 56 have been moved into engagement with the shoe rest 32 and the abutment 330 and the member 44 has been locked against rocking movement, the ironing plates 124, 218 and 154 at each side of the shoe are flexed 20 to conform more closely to the contour of the shoe bottom in response to pressure of the shoe upon them and yield downwardly against the resistance of the spring fingers 130, the U-shaped springs 206, and the spring fingers 160, until the fingers 25 130 engage the curved ribs 138, 140, the upper arms of the U-shaped springs 206 engage the pins 230 and the fingers 160 engage the plates 162. It will be understood that the plate 168 yields downwardly with the plates 154 in response to 30 pressure of the shoe upon it and that the plate 342 is flexed to conform to the contour of the plates 124 and also yields downwardly with the plates 124. Thereafter, or it may be during the downward yielding of the spring fingers 130 and 35 160 and the upper arms of the U-shaped springs 206, the different pairs of heated ironing plates at the opposite sides of the shoe are moved bodily inward over the shoe bottom in wiping engagement with the overlaid margin of the upper in 40 response to the swinging of the bell-crank levers 326 and as they are thus moved inwardly their pressure on the lasted margin of the upper is progressively increased as above described. As the ironing plates move inwardly over the shoe 45 bottom they act to tighten the upper over the bottom face of the insole along the sides of the forepart, shank and heel-end portions of the shoe and by applying progressively increasing pressure heightwise of the shoe to the overlaid margin of 50 the upper while subjecting it to the shrinking action of heat, they act to flatten the margin of the upper evenly and to iron it smoothly on the insole, thus preparing the bottom of the shoe in the best possible manner for the reception of the 55 outsole in a position close to the upper and insole. As more fully explained in the above-mentioned application Serial No. 201,790, as the ironing members complete their inward movements the overlaid margin of the upper is subjected to 60 further pressure by upward movement of the piston 80, after which the shoe is held under pressure by the movement of a valve into position to lock fluid under pressure in the cylinder 82. Thereafter the fluid is exhausted from the cylinder 82 and the slide 74 and the casting 84 by 65 their own weight slide downwardly on the rods 26, thereby releasing the shoe from pressure, the bell-crank levers 326 being swung in directions to move the ironing units away from each other 70 by the expanding of the spring 86. The slide 74 moves downwardly upon the rods 26 until a flange 348 (Fig. 1) on the slide engages the upper surface 350 of the cylinder 82, springs 352 surrounding links 354 pivotally connected to the 75

bracket 24 one at each side of the cylinder 82 yielding somewhat under the weight of the parts to permit this. The springs 352 bear at their lower ends against washers 356 engaging finished surfaces 358 on the bracket 24, washers 360 being provided between the upper ends of the springs 352 and the bracket 74. The links 354 are provided with elongated slots 362 through which extend pins 364 carried by the slide 74, the pins 10 364 engaging the links at the upper ends of the slots 362 to limit upward movement of the slide 74 and the piston 80 if the machine is operated with no shoe in the machine.

Having described the invention, what I claim as 15 new and desire to secure by Letters Patent of the United States is:

1. In a machine for pressing the bottoms of shoes, the combination with means for supporting a shoe against pressure applied on its bottom 20 face, of means for applying pressure to the bottom of the shoe after lasting but before an outsole is applied to the shoe comprising heated devices arranged to engage the bottom of the shoe along the opposite sides of its forepart, shank and 25 heel-end portions respectively, said devices being relatively adjustable heightwise of the shoe to accommodate shoes of different styles.
2. In a machine for pressing the bottoms of shoes, the combination with means for supporting a shoe against pressure applied on its bottom 30 face, of means for applying pressure to the bottom of the shoe after lasting but before an outsole is applied to the shoe comprising different pairs of devices arranged to engage the bottom 35 of the shoe along the opposite sides of its forepart, shank and heel-end portions respectively, said different pairs of devices being relatively adjustable heightwise of the shoe to accommodate shoes of different styles, and means for 40 moving said different pairs of devices inwardly over the bottom of the shoe in wiping engagement with the shoe bottom in response to resistance of the shoe to the pressure applied.
3. In a machine for pressing the bottoms of 45 shoes, the combination with means for supporting a shoe against pressure applied on its bottom face, of means for applying pressure to the bottom of the shoe after lasting but before an outsole is applied to the shoe comprising different 50 pressing members of resilient metal arranged to support a shoe placed initially thereon bottom downward by engagement with the bottom of the shoe along the opposite sides of its forepart, shank and heel-end portions respectively, said 55 different pressing members being relatively adjustable heightwise of the shoe to accommodate shoes of different styles, and each being flexibly conformable to the contour of the portion of the shoe bottom engaged thereby in response to pressure of the shoe thereon.
4. In a machine for pressing the bottoms of 60 shoes, the combination with means for supporting a shoe against pressure applied on its bottom face, of means for applying pressure to the bottom of the shoe after lasting but before an outsole is applied to the shoe comprising different 65 members of resilient metal arranged to engage the bottom of the shoe along the opposite sides of its forepart, shank and heel-end portions respectively, the members acting on the forepart, shank and heel-end portions of the bottom of the shoe being mounted in overlapping relation 70 lengthwise of the shoe, and said different members being relatively adjustable heightwise of the 75 shoe to accommodate shoes of different styles.

5. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to support a shoe placed initially thereon bottom downward by engagement with the bottom of the shoe along the opposite sides of its forepart, shank and heel-end portions respectively, said different pairs of plates being relatively adjustable heightwise of the shoe to accommodate shoes of different styles, means for moving said different pairs of plates inwardly toward each other in response to pressure of the shoe upon them, and means for progressively increasing the pressure of said plates on the bottom of the shoe during their inward movements.

6. In a machine for pressing the bottoms of 20 shoes, the combination with means for supporting a shoe against pressure applied on its bottom face, of means for applying pressure to the bottom of the shoe after lasting but before an outsole is applied to the shoe comprising different 25 pairs of members movable inwardly toward each other in wiping contact with the lasted margin of the upper at the opposite sides of the forepart, shank and heel-end portions of the shoe bottom respectively, the members of each pair 30 being shaped substantially to conform to the heightwise curvature of the portion of the shoe bottom engaged thereby, and said forepart and heel-end engaging members having portions overlapping said shank-engaging members to provide 35 continuous engagement with the lasted margin of the upper at each side of the shoe substantially from its toe to its heel-end portion, and means for heating said members.

7. In a machine for pressing the bottoms of 40 shoes, the combination with means for supporting a shoe against pressure applied on its bottom face, of means for applying pressure to the bottom of the shoe after lasting but before an outsole is applied to the shoe comprising different 45 pairs of resilient metal plates arranged to engage the bottom of the shoe along the opposite sides of its forepart, shank and heel-end portions respectively, the metal plates at each 50 side of the shoe being mounted in overlapping relation and each being flexibly conformable to the contour of the shoe in response to pressure of the shoe thereon, means for heating said different pairs of metal plates, and means for moving them simultaneously inward toward each 55 other in wiping engagement with the shoe bottom.

8. In a machine for applying pressure to the bottom of a shoe after lasting but before an outsole is applied to the shoe, the combination with 60 means for supporting a shoe against pressure applied on its bottom face, of pressure applying means comprising different pairs of resilient metal plates arranged to engage the bottom of the shoe at the opposite sides of its forepart, shank 65 and heel-end portions respectively, said different pairs of plates being shaped respectively to conform substantially to the heightwise curvatures of the forepart, shank and heel-end portions of the bottom of a shoe, and members connected together for tipping movements about axes extending laterally of the shoe for relatively adjusting said different pairs of plates heightwise of the shoe to vary their contour lengthwise of the shoe in accordance with variations in the heightwise 75

curvature of the bottoms of shoes of different styles.

9. In a machine for applying pressure to the bottom of a shoe after lasting but before an outsole is applied to the shoe, the combination with means for supporting a shoe against pressure applied on its bottom face, of pressure-applying means comprising metal plates arranged to engage the bottom of the shoe at the opposite sides of its forepart, shank and heel-end portions respectively, and means for tipping the forepart plates about an axis extending laterally of the shoe and for effecting simultaneously a movement of adjustment of said shank-engaging plates to vary the angle between said forepart and shank-engaging plates to accommodate shoes of different styles.

10. In a machine for applying pressure to the bottom of a shoe after lasting but before an outsole is applied to the shoe, the combination with means for supporting a shoe against pressure applied on its bottom face, of pressure applying means comprising different pairs of resilient metal plates arranged to engage the bottom of the shoe at the opposite sides of the forepart, shank and heel-end portions respectively, said different pairs of plates being shaped respectively to conform substantially to the heightwise curvatures of the forepart, shank and heel-end portions of the bottom of a shoe, means for tipping the forepart plates about an axis extending laterally of the shoe and for effecting simultaneously a movement of adjustment of said shank-engaging plates to vary the angle between said forepart and shank-engaging plates to accommodate shoes of different styles, and a scale for indicating different adjusted positions of said forepart and shank-engaging plates in operating upon shoes of different styles.

11. In a machine for applying pressure to the bottom of a shoe after lasting but before an outsole is applied to the shoe, the combination with means for supporting a shoe against pressure applied on its bottom face, of pressure-applying means comprising different pairs of resilient metal plates arranged to engage the bottom of the shoe at the opposite sides of its forepart, shank and heel-end portions respectively, said different pairs of plates being shaped respectively to conform substantially to the heightwise curvatures of the forepart, shank and heel-end portions of the bottom of a shoe, and means for relatively rotating the forepart and shank-engaging plates about an axis extending laterally of the shoe to vary the contour defined by said plates lengthwise of the shoe in accordance with variations in the heightwise curvature of the bottoms of shoes mounted on lasts designed to accommodate heels of different heights.

12. In a machine for applying pressure to the bottom of a shoe after lasting but before an outsole is applied to the shoe, the combination with means for supporting a shoe against pressure applied on its bottom face, of pressure-applying means comprising resilient metal plates arranged to engage the bottom of the shoe at the opposite sides of its forepart, shank and heel-end portions respectively, and means for relatively rotating said different pairs of plates about different axes extending laterally of the shoe and located substantially at the junction of the forepart and shank portions and at the junction of the shank and heel-end portions of the shoe to vary the contour defined by said plates lengthwise of the shoe

in accordance with variations in the heightwise curvature of the bottoms of shoes of different styles.

13. In a machine for pressing the bottoms of shoes, the combination with means for supporting a shoe against pressure applied on its bottom face, of means for applying pressure to the bottom of the shoe after lasting but before an outsole is applied to the shoe comprising a support, different pairs of resilient metal plates mounted on said support and arranged to engage the bottom of the shoe along the opposite sides of its forepart, shank and heel-end portions respectively, said plate support and the shoe support being relatively movable heightwise of the shoe, and separate means yieldable in response to such relative movement for forcing each of said resilient plates into conformity to the contour of the portion of the shoe bottom engaged thereby.

14. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to support a shoe placed initially thereon bottom downward by engagement with the bottom of the shoe along the opposite sides of its forepart, shank and heel-end portions respectively, a support common to all of said plates movable heightwise of the shoe, and separate means yieldable in response to the heightwise movement of said support for pressing each of said resilient plates into conformity to the contour of the portion of the shoe bottom engaged thereby.

15. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to engage the bottom of the shoe at the opposite sides of its forepart, shank and heel-end portions respectively, a movable support common to all of said plates, separate means yieldable heightwise of the shoe in response to the movement of said support for pressing each of said resilient plates into conformity to the contour of the portion of the shoe bottom engaged thereby, and means for limiting the yielding movements of said separate means.

16. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to support a shoe placed initially thereon bottom downward by engagement with the bottom of the shoe along the opposite sides of its forepart, shank and heel-end portions respectively, a movable support on which said plates are mounted for relative adjustment heightwise of the shoe to accommodate shoes of different styles, means acting on each of said plates to press it into conformity to the contour of the bottom of the shoe in response to movement of said support, mechanism for moving the different pairs of plates inwardly toward each other in wiping engagement with the shoe bottom, and means for progressively increasing the pressure of said plates on the bottom of the shoe during their inward movements.

17. In a machine for pressing the bottoms of shoes, the combination with means for supporting a shoe against pressure applied on its bottom face, of means for applying pressure to the bottom of the shoe after lasting but before an outsole is applied to the shoe comprising different pairs of flexible shoe-engaging plates arranged to engage the bottom of the shoe at the opposite sides of its forepart, shank and heel-end portions, respectively, the plates of each pair being shaped substantially to conform to the heightwise curvature of the portion of the shoe bottom engaged thereby, and different pairs of holders for supporting said different pairs of plates, said different pairs of holders being relatively adjustable heightwise of the shoe to position the plates for use in operating upon shoes of different styles.
18. In a machine for pressing the bottoms of shoes, the combination with means for supporting a shoe against pressure applied on its bottom face, of means for applying pressure to the bottom of the shoe comprising different pairs of resilient metal plates arranged to support a shoe placed thereon bottom downward by engagement with the bottom of the shoe along the opposite sides of its forepart, shank and heel-end portions respectively, said plates each being flexibly conformable to the contour of the shoe in response to pressure of the shoe thereon, and different pairs of holders for supporting said different pairs of plates, said holders being connected together for relative rotation about different axes extending laterally of the shoe to position the plates for use in operating upon shoes of different styles.
19. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to engage the bottom of the shoe at the opposite sides of its forepart, shank and heel-end portions, respectively, the plates of each pair being shaped substantially to conform to the heightwise curvature of the portion of the shoe bottom engaged thereby, and different pairs of holders for supporting said plates, said different pairs of holders being connected together for relative movement about different axes extending laterally of the shoe and located substantially at the junction of the forepart and shank portions and at the junction of the shank and heel-end portions of the shoe to position the plates for use in operating on shoes mounted upon lasts designed to accommodate heels of different heights.
20. In a machine for pressing the bottoms of shoes, the combination with means for supporting a shoe against pressure applied on its bottom face, of means for applying pressure to the bottom of the shoe after lasting but before an outsole is applied to the shoe comprising different pairs of resilient metal plates arranged to engage the bottom of the shoe at the opposite sides of its forepart, shank and heel-end portions respectively, the plates of each pair being shaped substantially to conform to the heightwise curvature of the portion of the shoe bottom engaged thereby, different pairs of holders for said plates, said different pairs of holders being connected together for relative rotation about different axes extending laterally of the shoe to position the plates for use in operating upon shoes of different styles, a support on which said holders are mounted for movements in directions laterally of the shoe, and mechanism for moving the holders at the opposite sides of the shoe simultaneously toward each other to impart bodily inward movements to said plates in response to resistance of the shoe to the pressure applied.
21. In a machine for applying pressure to the bottoms of shoes after lasting, the combination with means for supporting a shoe against pressure applied on its bottom face, of pressure-applying means comprising different pairs of pressing units arranged to engage the bottom of the shoe at the opposite sides of its forepart, shank and heel-end portions respectively, each of said units comprising a holder and a shoe-engaging plate of resilient metal shaped to conform substantially to the heightwise curvature of the portion of the shoe bottom engaged thereby, means for tipping said forepart units about an axis extending laterally of the shoe, and connections between said forepart units and said shank-engaging units for adjusting the shank-engaging units heightwise of the shoe in response to the tipping of said forepart units to vary the contour defined by said shoe-engaging plates lengthwise of the shoe in accordance with variations in curvature of the bottoms of shoes mounted on lasts designed to accommodate heels of different heights.
22. In a machine for pressing the bottoms of shoes, the combination with means for supporting a shoe against pressure applied on its bottom face, of means for applying pressure to the bottom of the shoe after lasting but before an outsole is applied to the shoe comprising different pairs of pressing units arranged to engage the bottom of the shoe at the opposite sides of its forepart, shank and heel-end portions respectively, said units each comprising a holder and a shoe-engaging plate of resilient metal shaped to conform substantially to the heightwise curvature of the portion of the shoe bottom engaged thereby, pivot pins extending laterally of the shoe and located substantially at the junction of the forepart and shank portions of the shoe for connecting the holders of said forepart and shank pressing units, and means for raising or lowering said pivot pins to vary the contour lengthwise of the shoe defined by said shoe-engaging plates.
23. In a machine for pressing the bottoms of shoes, the combination with means for supporting a shoe against pressure applied on its bottom face, of means for applying pressure to the bottom of the shoe after lasting but before an outsole is applied to the shoe comprising different pairs of pressing units arranged to engage the bottom of the shoe at the opposite sides of its forepart, shank and heel-end portions respectively, said units each comprising a holder and a shoe-engaging plate of resilient metal shaped to conform substantially to the heightwise curvature of the portion of the shoe bottom engaged thereby, said different pairs of holders being connected together by pivot pins extending laterally of the shoe and located substantially at the junction of the forepart and shank portions and at the junction of the shank and heel-end portions of the shoe, and means for raising or lowering said different pairs of pivot pins independently of each other to vary the contour lengthwise of the shoe defined by said shoe-engaging plates.
24. In means for ironing the bottoms of shoes, different pairs of ironing units movable toward each other laterally of a shoe to iron the bottom of the forepart, shank and heel-end portions of

the shoe respectively, each unit comprising a heated shoe-engaging plate flexibly conformable to the contour of the portion of the bottom of the shoe engaged thereby in response to pressure of the shoe thereon, and a movable support common to all of said units.

to bridge the space between the inner edges of the toe-engaging portions of said shoe-engaging plates and to engage the corresponding marginal portion of the upper during the inward movement of said shoe-engaging plates.

5

28. In means for ironing the bottoms of shoes, ironing units movable toward each other laterally of a shoe to iron the overlaid marginal portion of the upper along the opposite sides of the bottom of the shoe, said units each comprising a relatively thin shoe-engaging plate of resilient metal and a plurality of heavy spring fingers for supporting said shoe-engaging plate, said spring fingers being yieldable heightwise of the shoe to force said shoe-engaging plates into conformity to the contour of the shoe in response to pressure of the shoe on said shoe-engaging plates.

29. In means for ironing the bottoms of shoes, ironing units movable toward each other laterally of a shoe to iron the overlaid margin of the upper along the opposite sides of the bottom of the shoe, said units each comprising a relatively thin shoe-engaging plate of resilient metal and a plurality of substantially U-shaped springs for supporting said shoe-engaging plate, said U-shaped springs being yieldable independently of one another to force the shoe-engaging plate into conformity to the contour of the shoe in response to pressure of the shoe on said shoe-engaging plate.

30

gaging plate. 30. In means for ironing the bottoms of shoes, ironing units movable toward each other laterally of a shoe to iron the overlaid margin of the upper along the opposite sides of the bottom of the shoe, said units each comprising a shoe-engaging plate of resilient metal, a plurality of substantially U-shaped springs for forcing said shoe-engaging plate into conformity to the contour of the shoe in response to pressure of the shoe on said shoe-engaging plate, and a plurality of compression springs acting through said U-shaped springs to increase the pressure of said shoe-engaging plate on the shoe. 40
